C. E. CLARKE

VALVE GRINDER

Original Filed April 8, 1922

INVENTOR

CHARLES E. CLARKE

By *James E. Clarke*
his ATTYS.

UNITED STATES PATENT OFFICE.

CHARLES E. CLARKE, OF COLUMBUS, OHIO, ASSIGNOR OF ONE-THIRD TO BENTON F. STITT AND ONE-THIRD TO THOMAS F. FLOOD, BOTH OF COLUMBUS, OHIO.

VALVE GRINDER.

Application filed April 8, 1922, Serial No. 550,737. Renewed July 16, 1923.

To all whom it may concern:

Be it known that I, CHARLES E. CLARKE, a citizen of the United States, residing at Columbus, in the county of Franklin and State of Ohio, have invented a certain new and useful Improvement in Valve Grinders, of which the following is a specification.

The object of this invention is to provide an improved form of device for grinding the valves of engines—especially motor vehicle engines—whereby there is obtained simplicity and durability of construction, facility in assembling its component parts and efficiency in operation.

The invention is embodied in the example herein shown and described, the features of novelty being finally claimed.

In the accompanying drawing—

20 Figure 1 is a view partly in longitudinal section and broken out to show the interior construction.

Fig. 2 is a section on the line II—II Fig. 1.

25 Fig. 3 is an elevation of the clutch carrying spindle detached from the other parts.

In the views 5 designates the spindle, the clutch 6 for engaging the valve to be ground being pivoted to the lower end of the spindle

30 by a cotter pin. The spindle is cut away at opposite sides to form a neck 7 and recesses. Said neck is transversely perforated at 7^a to receive a removable journal 8 having its opposite ends provided with removable rollers 9, one in each of the recesses, the ends of said rollers projecting beyond the sides of the spindle.

10 designates an inner sleeve adapted to contain the spindle, said sleeve provided at 40 its lower end with diametrically arranged parallel spiral slots 11 in which the rollers 9 project and travel. The upper end of the sleeve 10 is closed and provided with a reduced externally threaded extension 12.

45 Said extension 12 is made of such diameter as to leave an ample annular shoulder at the end of the sleeve around the extension. Within the sleeve between the closed end thereof and the end of the spindle is a re- 50 movable coil spring 13 of sufficient resili-

ence to normally press the spindle with the rollers into a position where the rollers are arrested by the lower end of the spiral slots.

14 designates an outer sleeve fitting over 55 the inner sleeve and having at its upper end an inwardly projecting lip or flange 15 adapted to rest on the shoulder around the base of the threaded extension 12. Said outer sleeve 14 is of sufficient length to 60 cover the ends of the rollers 9 when the latter are in their fully depressed position and protect the hands of the user from injury in the operation of the device. The outer sleeve is clamped on the inner sleeve 65 by the internally threaded shank 16 of a handle 17, said shank turning on the threaded extension 12 and pinching the lip 15 on the shoulder of the inner sleeve around the base of said extension. When secured in place 70 the outer sleeve retains the rollers 9 on their journal.

The device is disassembled by removing the handle 17 and the outer sleeve 14 after which the rollers and their journaling pin 75 are removed thereby permitting the removal of the spindle and the coil spring. To assemble the parts this process is employed in reverse order.

The clutch which engages the valve to 80 be ground is rotated in one direction by depressing the handle 17 and then releasing the pressure and permitting the spring to rotate the spindle in the opposite direction.

With this construction there is very little 85 likelihood of injury to any of the parts and should they become worn they can be easily replaced.

The forms of the parts can be changed without departing from the gist of the invention as claimed.

What I claim is:

1. A valve grinding tool comprising, in combination, a spindle provided with removable bearings projecting transversely 95 therefrom, an inner sleeve provided with diametrically opposed spiral slots there-through engaging said bearings to rotate the spindle, a spring between the spindle and the inner sleeve, an outer sleeve covering the 100

inner sleeve and holding said projecting bearings in place and an operating handle for the sleeves.

2. A valve grinding tool comprising, in combination, a spindle provided with removable bearings projecting transversely therefrom, an inner sleeve provided with diametrically opposed spiral slots there-

through engaging said bearings to rotate the spindle, a spring between the spindle **10** and the inner sleeve, an outer sleeve covering the inner sleeve and holding said projecting bearings in place, and an operating handle connected with the inner sleeve and securing said outer sleeve.

CHARLES E. CLARKE.
